UNITED STATES PATENT OFFICE.

ROBERT P. GARSED, OF NORRISTOWN, PENNSYLVANIA.

OPERATING RAILWAY-SWITCHES.

SPECIFICATION forming part of Letters Patent No. 237,381, dated February 8, 1881.

Application filed September 10, 1880. (No model.)

To all whom it may concern:

Be it known that I, ROBERT P. GARSED, a citizen of the United States, residing at Norristown, in the county of Montgomery and State of Pennsylvania, have invented a new and useful Improvement in Air and Fluid Operated Railway-Switches, which improvement is fully set forth in the following specification and accompanying drawings, in which—

10. Figure 1 is a top or plan view of the improvement in railway-switches embodying my invention. Fig. 2 is a side elevation thereof, partly sectional. Fig. 3 is a transverse section thereof in line *x x*, Fig. 2. Fig. 4 is an enlarged view of a combined air and fluid pump. Figs. 5 and 6 are side elevations of different means for imparting motions to the pumping apparatus. Fig. 7 is a top or plan view of Fig. 5. Fig. 8 is a view of a modification of 20 the pump, and Fig. 9 is a view of a modification of the setting-arms of the switch.

Similar letters of reference indicate corresponding parts in the several figures.

My invention consists in operating an air 25 or fluid pump, or both, by the action of a passing train, and communicating the power of the air or fluid, or both, to the mechanism connected to the rails of the switch, whereby the switch may be shifted or opened and shut 30 with rapidity and power and without jarring, the operation being accomplished by a train passing in any direction.

Referring to the drawings, A represents the rails of the main track; B, the rails of the side 35 track or intersection, and C the rails of the switch. Adjacent to or a suitable distance from the pivoted end of the switch-rails are mounted two bevel-pinions, *a a*, both of which mesh with a bevel-pinion, *b*, having a vertical axis suitably mounted. Attached to each pinion *a* is a crank-shaft, *c*, extending transversely and carrying setting-rods *D*, which project in such manner that they may be struck or engaged by suitable wheels, levers, or other means connected to the train, under control of the engineer or other suitable person thereon. To the crank-shaft *c* are attached rods *d*, Fig. 4, which carry pistons *e* of pump cylinders or barrels *f*, which are located in a suitable pit beneath the road-bed. Passing from and communicating with the foot of each cylinder *f* is a pipe, *E E*, extending to the plunger-cylinders *F F'*, which are located in a suitable pit beneath the head

end of the switch, four such plunger-cylinders being shown in the present case. Above the 55 projecting ends or tops of the plungers *F'* of the cylinder is mounted a T-shaped arm, *G*, the horizontal limbs of which overhang said ends or tops of the plungers, and the upright limb is pivoted to the connecting-bar *H* of the 60 switch-rails, at the head thereof. Pivoted to opposite ends of the horizontal limb of the arm *G* are bent or curved levers *J*, resting at one 65 end on the top of the plungers *F'*, and having the other end engaging with bolts *K*, which are fitted to the horizontal limbs of the arm *G* and adapted to enter openings or keepers *g* in the side walls of the pit in which the plunger-cylinders *F* and arm *G* are located, springs *h* being connected to proper parts of said bolts 70 *K* and the arm *G*, for the purpose of returning said bolts to their normal positions in the openings or keepers *g*.

L represents a barrel or tank containing water, oil, or other fluid placed in the pit convenient to the pipes *E'*, which connect the plunger-cylinders *F*, the pipes *E''*, which connect the plunger-cylinders *F'*, communicating with said pipes *E'* and tank *L* by means of a four-way and *T*, *E'''*, each pipe *E'* having a check-valve, *k*, and each pipe *E''* having a check-valve, *k'*, the barrel or tank communicating with the pipes *E' E''* by means of a pipe, *L'*, and the four-way and *T E''*. The pipes *E''*, which communicate with the plunger-cylinders 85 *F''*, extend to and communicate with pump cylinders or barrels *f'*, located in a suitable pit or chamber opposite to the location of the barrels *f*, and crank-shafts *C*. Gearing *a b*, and setting-arm *D* are provided for operation of 90 the pistons of said pump cylinders or barrels *f'*.

The operation is as follows: When the train is approaching the switch in the direction of arrow 1 the proper person on the train depresses a lever or rod, shifts a wheel or other mechanism so as to strike the desired setting-arm, (in the present case on the right-hand side,) which is elevated. The effect of this is to rotate the relative crank-shaft *c* and operate the pump *e f*, the other crank-shaft *c* being 95 also rotated through the medium of the gearing *a b*, so as to raise the other setting-arm *D*. The pipes *E E' E'' E'''* are filled with fluid from the tank *L*, as are also the barrels *f* to the under side of the pistons. The descent of 100 the piston, by the action of the shaft *c*, as has

been stated, forces the fluid through the pipe E to the right-hand plunger-cylinder F, the plunger whereof is raised, thus pressing against the lower arms of the levers J, the first operation 5 whereof is to force the bolt K from the socket, opening, or keeper g, and next raise the adjacent limb of the arm G, thus throwing the bar H and connected switch-rails to the left, and setting the switch for the rails B B. Should 10 the next following train desire to run on the main tracks A A, the engineer or other person causes the left-hand setting-arm D to be struck, and thus, by the intermediate mechanism, the plunger of the left-hand cylinder F is raised, 15 thereby first releasing the respective bolt and then raising the adjacent end of the arm G, the switch-rails thus being thrown to the right and set for the main track, the parts being in position shown in Fig. 3. The right-hand setting-arm D has in the meantime been raised, 20 and is in position for the shifting of the switch to the left, when so desired. Should a train come from the opposite direction and the switch not having been shifted, by striking the setting-arm of the mechanism of the one that was previously struck and which was raised by the other being pressed down, the switch 25 will be adjusted to the other track; but should said train, by accident, strike the opposite setting-arm, the latter, or some part of the switch apparatus, would be broken; therefore that setting-arm is made of parts suitably jointed or hinged to remain stiff only by being struck from one direction and yielding in the opposite direction, the hinged part returning to its normal position by the action of a spring, 30 m, suitably applied, as in Fig. 2, it being evident that each setting-arm may be thus constructed. When the train is approaching 35 the switch in the direction of arrow 2 the operation is similar to that stated in the former case, the mechanism therefor being duplicated and located opposite to that for the train running in the direction of arrow 1, as has been 40 stated, and the crank-arms may be extended to other tracks for trains running to the switch.

It will be noticed that when the fluid is forced to one of the plunger-cylinders F, its pressure is not communicated to the opposite 45 plunger-cylinder F'. Consequently when one plunger of a cylinder F rises the other plunger is relieved from the pressure of the fluid and permitted to fall by the action of the descending limb of the arm G, the same condition 50 existing with the plunger-cylinder F''. When the plunger of the left-hand cylinder F rises, the plunger of the right-hand cylinder F'' is depressed and the fluid in the pipe E^x connected with said cylinder F'' is forced into 55 the barrel f' and raises the piston thereof, setting the arm D connected to the crank-shaft thereof. The piston of the other pump-barrel f' is depressed and forces the fluid in its pipe E^x into the left-hand piston-cylinder F'', thus 60 raising the plunger thereof, which is ready to be depressed by the next operation of the arm G through the movement of the setting-arm D.

It will also be noticed that as the check-valves k k' are placed between the tank L and pipes E E^x, the fluid is prevented from flowing back 70 into the tank under any pressure from the pipes E E^x, either from evaporation or otherwise. A constant supply of fluid may be maintained from the tank L, properly filled, as occasion requires.

In order to prevent any injurious effect of an increased pressure of the fluid, caused by accidental stopping of movement of any parts of the switch mechanism, I provide a safety valve or valves, M, which may be located on 80 any part of the pipes or cylinders, to open at a pressure somewhat below the bursting strength of said pipes; and in the present case the safety-valves are located upon an air-chamber, N, which communicates with the pipe E, the air 85 therein serving as a cushion for preventing jarring or concussion by the sudden operation of the switch mechanism.

In Fig. 4 I show a double piston, one above the other, the stem of the lower piston working through the center and tubular stem of the upper piston, each piston having a chamber or barrel, the two chambers or barrels being continuous and communicating.

It will be seen that when the connecting-rod d is operated and descends, say, three inches, the lower piston moves with it to the full extent of its stroke, and the air admitted to the upper cylinder through the openings n is compressed and acts on the lower piston, 90 and imparts further motion to the latter—say the distance of one inch or more—if provided for. The plunger of the cylinder F is thus lifted or raised, by the combined action of water or other liquid and air, by the two 95 pistons, the distance of four inches or more, if provided for by the adjustment of the two pistons. The air is introduced to act upon the lower piston the more to provide an elastic cushion for preventing jarring and concussion 100 in the operation of the switch.

The capacity of the lower part of the cylinder f regulates the height that the plunger F' is forced—as, for instance, a one-inch pipe, E, and two-inch cylinder f, with piston, being 115 used, and a stroke of one inch being given in cylinder f, the plunger F' is proportionately raised. The upper end of the barrel f has a cup or peripheral channel, p, at or about the base of which the openings n lead into the barrel, whereby when liquid alone is used, and when the piston e is raised above said openings, and the fluid in the barrel has a tendency to draw up or spill over the top of the barrel by the suction of the cylinder, it is caught by 120 the cup p, and returns, by its own weight, into the barrel through the openings n. When one of the plungers F' is up to its fullest extent, and the arm G, by the action of the plunger on the other side, forces the first-named 125 plunger down to its full extent, and if all of the air in the cylinder f had by accident escaped, the liquid pressing against the tightly-fitting piston in the lower part of the cylinder 130

f elevates the upper one to its full extent, and sets the setting-arm without permitting the escape of water above the lower piston. When air alone is used the lower piston is not essential;

5 and it is evident that I may use in my invention either air or liquid alone, or both air and liquid combined, as a vehicle for raising the plungers of the cylinders *F F'*, and the consequent shifting of the switch.

10 In Fig. 5 I show means for operating the pumps *e f*, in lieu of the crank-shafts *c*, Fig. 1. I employ an endless chain or band, *c*, which is passed around pinions *c'*, and has projecting arms *D* on its outer surface. The shafts 15 of said pinions carry cranks, to which the connecting-rods of the pumps *e f* are attached. It is evident that two pumps may thus be operated, and provision is made for pumping one or both of them, as long as the setting-arm is 20 carried along with the chain or band by the engagement of the lever, rod, wheel, &c., of the engine or other car.

25 A rack, *c*, and pinion *c'* may be employed, as in Figs. 5 and 6. On the upper face of the rack-bar is connected an upright pin, *D*, adapted to be shifted laterally, and return to its first position by a spring suitably applied. When said bolt is engaged by the lever, &c., of the engine or other car it is carried forward, and 30 with it the rack, thus rotating the crank-shaft of the pinion, and imparting motion to the connecting-rod of the pump. When the rack is about to complete its movement the pin *D* reaches an inclined slot in a guide-piece located at the end of the rack, whereby a lateral motion is imparted to the bolt, and it is carried clear of the lever, &c., of the engine, &c. When the motion of the rack is made it comes 35 in contact with a spring, as at *r*, and is thus thrown back the extent of the diagonal slot, and the pin is again placed in position to be struck or engaged by the next train. The rack at its ends is not toothed the distance that it rebounds from the slotted guide, in order to 40

45 avoid the rotation of the pinion on the rebound. By the employment of the endless chain or band and numerous strokes thereby imparted to the pump-piston *e*, where air is used alone, a check-valve is necessary to the 50 base of the pump-cylinder *f*, to prevent the return of the air to the pump at each stroke of the piston. In this case, instead of using plain plunger-cylinders under the arm *G*, I employ cylinders having perforations at or near the 55 top similar to those shown in Fig. 4, to permit the escape of the air, and allow the lowering of the plunger upon its depression consequent to the shifting of the switch.

60 In Fig. 7 I show three cylinders of a certain diameter, each provided with a piston, and adapted for forcing air or other fluid in a large volume through a pipe of less diameter to the plunger-cylinders.

65 The gearing *a b* may be dispensed with and the two crank-shafts *c* disconnected. In this case each shaft carries four setting-arms, *D*, and may have a wheel or disk, to which the

connecting-rods *d* are attached, the operation of each shaft being independent of the other, and the setting-rods adapted to work in either 70 direction.

If desired, hinged levers may be located outside of the tracks, and receive motion from some member of the passing train, and have the same imparted to the plungers *F'* of the 75 cylinders *F F'*, which latter may be upright or horizontal, the position of the arm *G* being arranged relatively thereto, and the pump-cylinders *f* may be either horizontal or upright.

The subject-matter of Fig. 5 is described and 80 claimed in a prior application of mine now allowed. Hence I do not claim it in this application.

Having thus described my invention, what I claim as new, and desire to secure by Letters 85 Patent, is—

1. In combination with two shafts geared to turn in opposite directions and setting-arms carried thereby, two liquid-forcing pistons, each of which is operated by one of said shafts, 90 a lever which moves the switch-rails from side to side, and tubular connections arranged to allow fluid to be forced through them by said pistons and to move said lever in either direction. 95

2. The combination of reservoir *L*, connected system of pipes *E E' E'' E'''*, cylinders *f F F'*, and their pistons, with the shafts *c*, geared together, and the lever for shifting the switch-rails. 100

3. A T-shaped switch-shifting lever provided with latches for locking the same at the end of either vibration, and a pneumatic or hydraulic apparatus arranged to vibrate the said lever in either direction, at will, and to withdraw the opposite latch, substantially as set forth. 105

4. A fluid-forcing piston having a supplementary piston attached thereto, and the latter being allowed an independent forward motion after the former stops. 110

5. The arm *G*, with bolts *K*, in combination with the levers *J* and plungers *F'*, whereby said bolts are released in advance of the movement of said arm, substantially as and for the 115 purpose set forth.

6. The cylinder *f*, provided with the cup *p*, and perforations *n*, substantially as and for the purpose set forth.

7. The setting-arms, formed of parts hinged 120 together and formed with restoring springs, substantially as and for the purpose set forth.

8. The series of pipes *E' E''*, with check-valves *k* and the tank *L*, in combination with the plungers and cylinders *F F' F''* and the 125 pumping mechanisms, substantially as and for the purpose set forth.

9. The fluid-operated switch and pumping mechanism, in combination with one or more air-chambers and a safety valve or valves, substantially as and for the purpose set forth. 130
